PUMP

William Gerrard, Timperley, and Walter Harris,
Altrincham, England, assignors to Linotype
and Machinery Limited, London, England, a
limited-liability company of Great Britain

Application November 30, 1940, Serial No. 367,902
In Great Britain November 30, 1939

18 Claims. (Cl. 103—41)

This invention relates to improvements in reciprocating pumps and is particularly, but not exclusively, adapted to metal pumps such as are employed in stereotype plate casting machines. Such metal pumps are usually provided with a spout or throat pipe communicating with a mold or other receptacle up which the molten metal which is to be cast into a stereotype plate passes under the operation of the plunger. A bypass valve is generally provided through which the molten metal is admitted to the pump cylinder.

The present invention provides a reciprocating pump adapted to discharge liquid to a mold or other receptacle having a bypass valve in the pump cylinder and mechanism for opening the said valve when the mold or receptacle is full or when a predetermined quantity of liquid has been delivered to permit the escape of excess liquid.

The said mechanism may be actuated by the means for reciprocating the pump plunger and preferably the said plunger is reciprocated by means of a pump lever which is provided with a stop thereon the said stop being adjustable to enable the valve to be opened at the appropriate moment and adapted to engage a member which controls the opening of the bypass valve.

The pump lever may be manually operated or, in the alternative, power operated means may be provided for actuating the same. In the construction where it is designed for manual operation, a manual control is advantageously provided for closing the valve. Where, however, the lever is operated by power means, the arrangement is preferably such that the said power means are set in motion by the same control that closes the valve.

In order that the invention may be more clearly understood the same will now be described in detail with reference to the accompanying drawings which illustrate the same as applied to a pump for molten metal adapted for filling molds for casting stereotype printing plates.

In these drawings—

Figure 1 is a side view in section of an embodiment of the invention wherein the pump is manually operated.

Figure 2 is an end view of Figure 1 in the direction of the arrow "A."

Figure 3 is a side view in section of a further embodiment of the invention wherein the pump is operated by mechanical means.

Figure 4 is a view of Figure 3 in the direction of the arrow "B," with parts broken away.

Figure 5 is a plan view of the construction of Figures 3 and 4.

Referring first to Figures 1 and 2, the pump cylinder 1 is vertically disposed within a melting pot 2 which contains the molten metal 3 used for casting the plates and a spout 4 leads from the cylinder 1 to the mold in which the stereotype plate is cast. The pump plunger 5 is connected to a pump plunger rod 6 which extends vertically through a hole 7 in the cylinder and is connected at a point 8 at or near its upper end to a pump lever 9 which is pivotally mounted in a bearing 10 located in the main framework of the machine. A stop 11 is mounted on one side of the said pump lever 9 in a bracket 12 thereon and is adjustable lengthwise of the said bracket by means of a screw 13 or by other suitable means. The said stop 11 is adapted to engage the upper end of a valve adjusting rod 14 at a certain desired point on its downward travel and to force the same downwards in a vertical direction when the pump lever 9 is moved about its pivot 10 so as to raise the pump plunger 5 in the cylinder 1 and deliver metal up the spout 4 into the casting mold. The valve adjusting rod 14 is mounted in a suitable bracket 15. The lower end of the valve adjusting rod 14 is connected to a lever 16 which extends substantially horizontally and is mounted on a valve operating rod 17. A second substantially horizontal connecting lever 18 is attached to the valve operating rod 17, the other end of which is pivoted to the upper end of a valve rod 19. The lower end of the valve rod 19 is attached to a bypass valve 20 of inverted mushroom type which seats in the upper part of the pump cylinder 1. In Figure 1 the valve is shown in the closed position in full lines and in the open position in dotted lines.

It is to be observed that upon depression of the right hand end of the pump lever 9 the pump plunger 5 is raised, causing molten metal to be pumped up the spout 4 to the mold. At the same time the stop 11 on the pump lever 9 engages the top of the valve adjusting rod 14 at the appropriate moment and depresses the same, causing the valve operating rod 17 to be rotated and the valve rod 19 to be depressed through the operation of the connecting lever 18 above referred to. The valve 20 is thus opened at a moment which depends on the adjustment of the position of the stop 11 on the pump lever 9 relatively to the top of the valve adjusting rod 14 and normally this position is arranged so that the valve 20 opens when the casting mold has been filled so that continued movement of

the pump plunger 5 enables any excess of molten liquid to escape from the pump cylinder 1 to the melting pot. The closing of the valve 20 is effected at the appropriate time by rotation of the valve operating rod 17 by means of a handle 21.

The machine may, as described, be manually operated by actuation of the pump lever but power operated means may be provided for this purpose and the same may be advantageously employed in the case of larger machines where a substantial weight of metal requires to be raised. Such an arrangement is shown in Figures 3, 4 and 5. In these drawings the driving power is provided by an electric motor 22 mounted upon the main framework of the machine which transmits power to a shaft 23 at reduced speed. The shaft 23 is conveniently mounted in a bracket 24 and carries a worm 25 which is in mesh with a worm wheel 26 which in turn is mounted on a transverse shaft 27. The said worm wheel 26 is provided with a projecting stud 28 which is connected with the pump lever 9 by means of a link 29 in such a manner that rotation of the worm wheel 26 causes reciprocation of the pump lever 9 and actuates the pump plunger 5.

The worm wheel 26 is provided with a cam-disc 30 which is formed at one point on its circumference with a recess 31 which is adapted to receive a roller 32 which runs upon the disc 30 and which is mounted on one end of an arm 33 which is loosely pivoted on the valve operating rod 17. When the worm wheel disc 30 turns round to a position where the recess 31 is in position to receive the roller 32, the arm 33 is free to fall so that the roller 32 engages in the recess 31. The said arm 33 is also provided with an extension 34 projecting beyond the valve operating rod 17 the free end of which carries a rod 35 which rod is connected to a switch (not shown). This switch controls the electric motor 22, the arrangement being such that when the roller 32 falls into the recess 31 the switch breaks the circuit controlling the motor 22 and rotation of the worm wheel 26 ceases. For so long, however, as the roller 32 is upon the higher part of the disc 30 the circuit remains closed and the electric motor is in operation so that the pump plunger 5 operates.

The valve operating rod 17 is mounted in bearings and is provided at its free end with a handle 21 by means of which it may be manually rotated. A coiled tension spring 36 is provided on this shaft one end of which is held in the shaft bearings and the other end of which engages the roller arm 33 so as to hold the roller 32 against the disc 30 and to ensure that the same drops into position in the recess 31 in the said disc 30 when it is opposite the same. A pin or stud 37 is provided on the roller arm 33 which is adapted to engage an arm 38 which is firmly fixed upon the valve operating rod 17 so that rotation of the rod 17 by the lever 21 to the appropriate amount causes the roller arm 33 to be moved through an arc to such an extent that the roller 32 may be withdrawn from its recess 31.

The operation of the arrangement is controlled by manual operation of the handle 21 of the valve operating rod 17. Rotation of this rod closes the valve 20 and causes the roller 32 to be withdrawn from the recess 31 in the manner just described. The switch which sets the electric motor 22 in operation is also closed by

movement of the extension 34 of the roller arm 33 and the worm wheel 26 is set in rotation by the motor 22 causing the pump plunger 5 to be set in motion. At the end of one rotation of the worm wheel 26 the roller 32 falls into the recess 31 in the disc 30 and the switch is disconnected. The machine is thereby brought to rest and manual operation of the valve operating rod handle 21 is required to set the same into operation again to effect another stroke of the pump plunger 5. The valve 20 is opened at the appropriate time in the same manner as already described with reference to Figures 1 and 2.

Having described our invention, we declare that what we claim and desire to secure by Letters Patent is:

1. In a reciprocating pump adapted to discharge liquid to a receptacle, the combination of a pump cylinder, a pump plunger therein, a by-pass valve in said cylinder, automatic means for opening said valve after delivery of a predetermined quantity of liquid, a pump lever connected to said pump plunger, a worm wheel connected by means of a link to said pump plunger, power operated means for driving said worm wheel, a cam disc carried by said worm wheel and having a recess therein, a cam roller held in engagement with said cam disc, and means for simultaneously raising said cam roller from said recess and for setting said power operated means in motion.

2. In a reciprocating pump adapted to discharge liquid to a receptacle, the combination of a pump cylinder, a pump plunger therein, a by-pass valve in said cylinder, automatic means for opening said valve after delivery of a predetermined quantity of liquid, a pump lever connected to said pump plunger, a worm wheel connected by means of a link to said pump plunger, power operated means for driving said worm wheel, a cam disc carried by said worm wheel and having a recess therein, and a cam roller engaging said cam disc, said cam roller being mounted on an arm which is loosely mounted on a shaft, said roller being held in engagement with said cam disc by means of a torsion spring engaging said arm and the shaft bearing, and said shaft being connected to the control for said power operated means.

3. In a reciprocating pump adapted to discharge liquid to a receptacle, the combination of a pump cylinder, a pump plunger therein, a by-pass valve in said cylinder, automatic means for opening said valve after delivery of a predetermined quantity of liquid, a pump lever connected to said pump plunger, a worm wheel connected by means of a link to said pump plunger, power operated means for driving said worm wheel, a cam disc carried by said worm wheel and having a recess therein, a cam roller engaging said cam disc, said cam roller being mounted on an arm which is loosely mounted on a shaft, said roller being held in engagement with said cam disc by means of a torsion spring engaging said arm and the shaft bearing, said arm carrying a stud, and a second arm fast on said shaft adapted to engage said stud, said shaft being connected to the control for said power operated means.

4. In a reciprocating pump adapted to discharge liquid to a receptacle, the combination of a pump cylinder, a pump plunger therein, a by-pass valve in said cylinder, automatic means for opening said valve after delivery of a predetermined quantity of liquid, a pump lever con-

nected to said pump plunger, a worm wheel connected by means of a link to said pump plunger, power operated means for driving said worm wheel, a cam disc carried by said worm wheel and having a recess therein, a cam roller engaging said cam disc, said cam roller being mounted on an arm which is loosely mounted on a shaft, said roller being held in engagement with said cam disc by means of a torsion spring engaging said arm and the shaft bearing, said arm carrying a stud, and a second arm fast on said shaft and adapted to engage said stud, said shaft being connected to the control for said power operated means and to said by-pass valve, the arrangement being such that rotation thereof actuates said power operated means to set said worm wheel in motion and closes said valve.

5. In a reciprocating pump adapted to discharge liquid to a receptacle, the combination of a pump cylinder, a pump plunger therein, a by-pass valve in said cylinder, a pump lever connected to said pump plunger and having an adjustable stop thereon, means engaged by said stop to open said by-pass valve after delivery of a predetermined quantity of liquid, a worm wheel connected by means of a link to said pump plunger, power operated means for driving said worm wheel, a cam disc carried by said worm wheel and having a recess therein, a cam roller held in engagement with said cam disc, and means for simultaneously raising said cam roller from said recess and for setting said power operated means in motion.

6. In a reciprocating pump adapted to discharge liquid to a receptacle, the combination of a pump cylinder, a pump plunger therein, a by-pass valve in said cylinder, a valve operating rod therefor, a pump lever connected to said plunger and having an adjustable stop thereon, a valve adjusting rod connected by levers to said valve operating rod, said stop engaging said valve adjusting rod to open said by-pass valve after delivery of a predetermined quantity of liquid, a worm wheel connected by means of a link to said pump plunger, power operated means for driving said worm wheel, a cam disc carried by said worm wheel and having a recess therein, a cam roller engaging said cam disc, said cam roller being mounted on an arm which is loosely mounted on a shaft, said roller being held in engagement with said cam disc by means of a torsion spring engaging said arm and the shaft bearing, said arm carrying a stud, and a second arm fast on said shaft adapted to engage said stud, said shaft being connected to the control for said power operated means and to said valve operating rod, the arrangement being such that rotation thereof actuates said power operated means to set said worm wheel in motion and closes said by-pass valve.

7. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump plunger is filled to capacity when the pump plunger is at the lower end of its stroke notwithstanding variations in the level of the liquid in the pot and which is closable prior to the inauguration of the active stroke of the pump plunger, and automatic means for opening said valve during the delivery stroke of the pump plunger and at some predetermined

period before the completion of said stroke, whereby a predetermined quantity of liquid will be delivered from the pump cylinder at each stroke of the pump plunger.

- 5   8. In a reciprocating pump adapted to discharge liquid from a pot to a receptacle, the combination of a pump cylinder located in the pot, a pump plunger therein, an inlet and outlet valve located adjacent the top of the cylinder to insure
10   that the cylinder at each operation of the pump plunger is filled to capacity when the pump plunger is at the lower end of its stroke notwithstanding variations in the level of the liquid in the pot and which is closable prior to the inauguration of
15   the active stroke of the pump plunger, means for reciprocating said pump plunger, with mechanism whereby said reciprocating means causes said valve to open during the delivery stroke of the pump plunger and at some predetermined
20   period before the completion of said stroke, whereby a predetermined quantity of liquid will be delivered from the pump cylinder at each stroke of the pump plunger.

9. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump
25   plunger is filled to capacity when the pump plunger is at the lower end of its stroke notwithstanding variations in the level of the liquid in the pot and which is closable prior to the inauguration of the active stroke of the pump plunger, and a
30   pump lever connected to said pump plunger and having an adjustable stop thereon, with means engaged by said stop to open said valve during the delivery stroke of the pump plunger and at some predetermined period before the completion
35   of said stroke, whereby a predetermined quantity of liquid will be delivered from the pump cylinder at each stroke of the pump plunger.

40   10. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump
45   plunger is filled to capacity when the pump plunger is at the lower end of its stroke notwithstanding variations in the level of the liquid in the pot and which is closable prior to the inauguration of the active stroke of the pump plunger, a valve operating rod, a pump lever connected to
50   said pump plunger and having an adjustable stop thereon, and a valve adjusting rod connected by levers to said valve operating rod, said stop engaging said valve adjusting rod to open said valve during the delivery stroke of the pump plunger
55   and at some predetermined period before the completion of said stroke, whereby a predetermined quantity of liquid will be delivered from the pump cylinder at each stroke of the pump plunger.

60   11. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump
65   plunger is filled to capacity when the pump plunger is at the lower end of its stroke notwithstanding variations in the level of the liquid in the pot and which is manually closable prior to the inauguration of the active stroke of the pump
70   plunger, and automatic means for opening said
75   plunger, and automatic means for opening said

valve during the delivery stroke of the pump plunger and at some predetermined period before the completion of said stroke, whereby a predetermined quantity of liquid will be delivered from the pump cylinder at each stroke of the pump plunger.

12. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump plunger is filled to capacity when the pump plunger is at the lower end of its stroke notwithstanding variations in the level of the liquid in the pot, a valve operating rod, a manually operated pump lever connected to said pump plunger and having an adjustable stop thereon, a valve adjusting rod connected by levers to said valve operating rod, said stop engaging said adjusting rod to open said valve during the delivery stroke of the pump plunger and at some predetermined period before the completion of said stroke, whereby a predetermined quantity of liquid will be delivered from the pump cylinder at each stroke of the pump plunger, and a manual control on one of said levers for closing said valve.

13. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump plunger is filled to capacity when the pump plunger is at the lower end of its stroke notwithstanding variations in the level of the liquid in the pot, manual means for closing said valve, power operated means for reciprocating said plunger and mechanism whereby said reciprocating means causes said valve to open during the delivery stroke of the pump plunger and at some predetermined period before the completion of said stroke, whereby a predetermined quantity of liquid will be delivered from the pump cylinder at each stroke of the pump plunger.

14. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump plunger is filled to capacity when the pump plunger is at the lower end of its stroke notwithstanding variations in the level of the liquid in the pot, manual means for closing said valve, a pump lever connected to said pump plunger and having an adjustable stop thereon, power operated means for actuating said pump lever, means engaged by said stop to open said valve during the delivery stroke of the pump plunger and at some predetermined period before the completion of said stroke, whereby a predetermined quantity of liquid will be delivered from the pump cylinder at each stroke of the pump plunger.

15. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump plunger is filled to capacity when the pump plunger is at the lower end of its stroke notwithstanding variations in the level of the liquid in

the pot, power operated means for reciprocating said plunger, mechanism whereby said reciprocating means causes said valve to open during the delivery stroke of the pump plunger and at some predetermined period before the completion of said stroke, whereby a predetermined quantity of liquid will be delivered from the pump cylinder at each stroke of the pump plunger, and a common manual control for closing said valve and setting said power operated means in motion.

16. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump plunger is filled to capacity when the pump plunger is at the lower end of its stroke notwithstanding variations in the level of the liquid in the pot, power operated means for reciprocating said plunger, mechanism whereby said reciprocating means causes said valve to open during the delivery stroke of the pump plunger and at some predetermined period before the completion of said stroke, whereby a predetermined quantity of liquid will be delivered from the pump cylinder at each stroke of the pump plunger, a common manual control for closing said valve and setting said power operated means in motion.

17. In a reciprocating pump adapted to discharge liquid from a pot to a receptacle, the combination of a pump cylinder located in the pot, a pump plunger therein, an inlet and outlet valve located adjacent the top of the cylinder to insure that the cylinder at each operation of the pump plunger is filled to capacity when the pump plunger is at the lower end of its stroke notwithstanding variations in the level of the liquid in the pot, a pump lever connected to said pump plunger having an adjustable stop thereon, means engaged by said stop to open said valve during the delivery stroke of the pump plunger and at some predetermined period before the completion of said stroke, whereby a predetermined quantity of liquid will be delivered from the pump cylinder at each stroke of the pump plunger, power operated means for actuating said pump lever, a common manual control for closing said valve and setting said power operated means in motion and automatic means for disconnecting said power operated means on completion of an upward and downward stroke of the pump plunger.

18. In a reciprocating pump adapted to discharge liquid from a pot to a receptacle, the combination of a pump cylinder located in the pot, a pump plunger therein, said cylinder at each operation of the pump plunger being filled to capacity when said plunger is at the lower end of its stroke notwithstanding variations in the level of the liquid in the pot, a by-pass valve in the pump cylinder, and automatic means for opening said valve during the delivery stroke of the pump plunger and at some predetermined period before the completion of said stroke, whereby a predetermined quantity of liquid will be delivered from the pump cylinder at each stroke of the pump plunger.

WILLIAM GERRARD,
WALTER HARRIS.
